DESIGN FOR A PLAYING CARD HOLDER

Reginald S. Wattley, New York, N. Y.

Application October 28, 1947, Serial No. 142,173

Term of patent 7 years

(Cl. D34—13)

To all whom it may concern:

Be it known that I, Reginald S. Wattley, a citizen of the United States, residing at New York, in the county of New York and State of New York, have invented a new, original, and ornamental Design for a Playing Card Holder, of which the following is a specification, reference being had to the accompanying drawing, forming part thereof.

I claim:

The ornamental design for a playing card holder, as shown.

REGINALD S. WATTLEY.
